UNITED STATES PATENT OFFICE.

WILLARD D. RICHARDSON, OF COLUMBUS, OHIO.

BUILDING-WALL STRUCTURE.

Application filed February 25, 1925. Serial No. 11,545.

My invention relates to a building wall structure and is particularly concerned with the provision of a facing surface of any desired color and texture to be employed where 5 a building wall having a glazed brick exterior is desired.

In the past, it has been the practice when constructing building or other walls having an exterior facing of finer material than the 10 body of the wall, to construct the body portion of the wall from ordinary bricks and then to place a course of facing bricks of the desired color and texture on the exterior. This practice has necessitated the buying, 15 transportation and handling of facing bricks of standard size, and since facing bricks are not ordinarily so easily obtained as common building bricks it has sometimes been necessary to transport them great distances at an almost prohibitive cost. Furthermore, the initial cost of standard size facing bricks is relatively higher than that 20 of common bricks because of the higher grade material and the more careful and expensive processes necessary to produce the same.

My invention contemplates the construction of faced brick walls from facing bricks which are less expensive than those ordinarily employed, though of equal quality and texture. Both sizes of bricks employed in my novel wall structure are preferably perforated to reduce the weight, but further, only half of the facing bricks are of standard size, the others being preferably less than half the size of a standard brick. Because of the arrangement of units in my novel wall structure, the manner of bonding the units and the employment of a substantial burden bearing unit, it is possible to make the facing units much lighter in weight because very little of the actual building weight is supported by them.

The primary object of my invention is to 45 provide wall facing materials which are lighter in weight, cheaper in first cost and from which a wall having the desired exterior facing can be built much more cheaply than where standard size facing bricks are used.

A further object of my invention is the construction of a fireproof building wall having confined air spaces between the burden bearing and facing units thereof, which 55 spaces will form an insulating means for the building and prevent the heat from being

carried away by convection currents. This structural feature also results in a substantial and durable wall which, because of its arrangement and hollow construction, presents a great saving in material and labor.

A still further object of my invention is to construct a building wall in such a manner that continuous mortar joints between the exterior and the interior of the wall will 60 be eliminated. Continuous mortar joints act as capillary paths and conduct moisture from the exterior of the wall to the interior thereof, where it often results in loosening or damaging the plaster or paper with 65 which the interior of the wall may be covered.

Many other features of my invention will be apparent as this description progresses and will be brought out in the claims appended hereto. The various objects of my invention are preferably obtained by the structure illustrated in the accompanying drawings, wherein similar reference characters designate corresponding parts, and 70 wherein:

Figure 1 is a perspective view of the small facing brick used to construct alternate courses of my novel building wall.

Figure 2 is a perspective view of the large 85 facing brick, which is preferably of standard size.

Figure 3 is a perspective view of a wall constructed and faced according to my invention.

Figure 4 is a vertical section of a wall constructed according to my invention, and showing the manner of arranging the various courses of bricks where standard sized bricks are used for the burden bearing unit.

Figure 5 is a vertical section of my building wall showing the method of constructing and arranging the various courses where tiles are used for forming the burden bearing unit.

In the drawings and with particular reference to Figures 3 and 4, my invention is shown as comprising a plurality of vertical parallel bonded courses of bricks which are secured to each other by alternate courses 105 of header bricks. Two units A and B are shown; A being a burden bearing structure comprising alternate layers of stretchers 1 and headers 2 bonded with mortar. Extending parallel with the burden bearing 110 structure A is a vertical course of facing bricks B formed as shown in Figure 4 of

2 alternate courses of standard size perforated facing bricks 3, which are disposed between and bonded to the headers 2 of the burden bearing unit A.

5 Opposite the ends of the headers 2 of the unit A and disposed between the standard sized facing bricks 3 are the facing bricks 4. These facing bricks 4 have approximately half, or less than half of, the 10 bearing surface of a standard sized brick; the other dimensions being preferably the same as a standard brick. The facing bricks 3 and 4 are preferably perforated to reduce the weight, since it is desirable that this 15 facing unit support only a small percentage of the total building weight. It is understood that the exact form of the facing bricks, as shown in Figures 1 and 2, and the size and shape of the perforations 20 therein may vary considerably and that if desired the facing bricks 3 and 4 may be formed solid.

In Figure 5, I have shown a modified 25 method of constructing my building wall structure, which may be used when the burden bearing unit A is built up largely of hollow tiles or blocks instead of standard bricks. In this case, two of the smaller 30 facing bricks 4 are placed opposite the end 35 of the tile headers 2 of the burden bearing unit A.

It will be noted in Figures 3, 4 and 5 35 that the bonding mortar 5 between the bricks does not extend entirely through the wall and that at no place is there a continuous mortar joint which might act as a 40 capillary path to conduct moisture from the exterior of the wall to the interior. It will also be noted that the building wall as 45 constructed is formed with insulating air cushions 6 between the burden bearing or interior surface A of the wall and the facing or exterior surface B. It is well known that dead or quiescent air is a good insulator 50 and a poor conductor of heat. The alternate courses of header bricks 2 between the burden bearing and facing units will also prevent convection of the heat between these 55 two units.

59 From the foregoing description, it will be obvious that I have produced a building wall structure which can be inexpensively faced with bricks of the desired color and texture, a building wall which is effectively

insulated against movement of heat there- 55 through; and a wall structure which has ob- viated one of the most common objections 60 against masonry walls, which is the passage of water or moisture through the wall, which results in much damage to the in- 65 terior surface, weakens the walls and makes the interior of a building damp and disagreeable.

Having described my invention, what I 65 claim is:

1. A wall structure comprising a burden bearing unit formed of alternate courses of headers and stretchers of standard size, a parallel facing unit formed in part of standard sized facing bricks positioned be- 70 tween the header courses of said burden bearing unit and formed in part with courses of narrower facing bricks bonded to the ends of the headers of the burden bear- 75 ing unit by the standard sized courses of facing bricks.

2. A wall structure comprising an inner 80 wall formed of courses of headers and stretchers and an outer parallel wall bonded to the header courses of the inner wall and being formed in part of standard sized units and in part of units, two of the dimensions of which are standard and the third dimen- 85 sion or bearing surfaces less than half standard.

3. A wall structure comprising a burden- 90 bearing unit formed of alternate courses of headers and stretchers, a parallel facing unit formed in part of standard sized facing bricks partially positioned between the header courses of said burden-bearing 95 unit and alternating with courses of smaller facing bricks bonded to the ends of the headers of the burden-bearing unit by the courses of standard sized facing bricks.

4. A wall structure comprising a unit 100 constructed of standard size pieces, alternate rows of which pieces project beyond the rows which they embrace, and a facing unit comprising standard facing brick, alternate rows of which facing bricks embrace such projecting rows and themselves further project, and comprising smaller facing bricks 105 embraced by the projecting portions of said standard facing bricks.

In testimony whereof I, hereby affix my signature:

WILLARD D. RICHARDSON.
